(57) **CLAIM**

The ornamental design for a vehicle, as shown and described.

DESCRIPTION

FIG. 1 is a front perspective view of a vehicle showing my new design without a panoramic roof;

FIG. 2 is a rear perspective view of a vehicle without a panoramic roof;

FIG. 3 is a left side view of a vehicle without a panoramic roof;

FIG. 4 is a right side view of a vehicle without a panoramic roof;

FIG. 5 is a front view of a vehicle without a panoramic roof;

FIG. 6 is a rear view of a vehicle without a panoramic roof;

FIG. 7 is a top view of a vehicle without a panoramic roof;

FIG. 8 is a front perspective view of a vehicle without a panoramic roof;

FIG. 9 is a rear perspective view of a vehicle without a panoramic roof;

FIG. 10 is a left side view of a vehicle showing a second embodiment of my new design with a panoramic roof;

FIG. 11 is a right side view of a vehicle with a panoramic roof;

FIG. 12 is a front view of a vehicle with a panoramic roof;

FIG. 13 is a rear view of a vehicle with a panoramic roof; and,

FIG. 14 is a top view of a vehicle with a panoramic roof.

Portions of FIGS. 1-14 that are shown in dashed lines are for illustrative purpose only and form no part of the claimed design.
